CORSET ATTACHMENT

Josephine L. Holt, Oakland, Calif.

Application March 2, 1946, Serial No. 651,534

1 Claim. (Cl. 2-38)

1

This invention relates to corsets having special abdominal supports and especially to a garment of this character particularly designed for very corpulent people.

The principal object of the invention is to provide an insert or attachment for such a corset which will enable persons of different abdominal proportions to be properly fitted with a minimum number of corset sizes. By this means, a few standard sizes of corsets, with corresponding reduction of cost both to the corset seller and to the customers, will satisfy all needs.

Also, abnormally fat people are apt to increase in their abdominal girth, and my insert enables the same corset to be readily adjusted to take care of this increase without the need of purchasing an entirely new outfit every time.

In the drawings:

Figure 1 is an elevation of an insert, looking at the outer face thereof.

Figure 2 is an edge view of the insert.

Figure 3 is an elevation of the insert on the side opposite that shown in Figure 1.

Figure 4 is a cross section of the insert as mounted on a corset, taken on line 4-4 of Figure 6.

Figure 5 is a perspective view of the insert as mounted in connection with the abdominal support of a corset.

Figure 6 is a fragmentary elevation of the insert as mounted on a corset.

Referring to the numerals of reference on the drawings, a typical corset 1, to which my invention may be applied includes a front abdominal portion 2, terminating in a free edge and having a row of lacing eyelets 3, down the same, and a narrow strip 4, on the corset opposite said free edge and provided with a row of hook eyelets 5.

The gap between portion 2, and strip 4, varies with the corpulence of the wearer and is ordinarily bridged by lacing which frequently must be so long that bulging and chafing of the skin occurs between the solid portions of the corset, to the discomfort of the wearer.

This objectional feature is eliminated by my invention, which comprises essentially a strip 6, of strong webbing or elastic fabric. This strip is as long as the height of corset portion 2, and may be as wide as may be required.

Down one edge, the strip is provided on one side with a row of hooks 7, for detachable engagement with the eyelets 5, as shown in Figure 6. Down its other edge, the strip is provided with a row of lacing eyelets 8, which are thus disposed in opposed relation to the corset eyelets 3.

Lacing 9, connects strip 1, and corset portion 2, through eyelets 8, and 3, and since it is extremely easy to replace strip 1, with a similar wider one with any increase in corpulence of the wearer, the space which is spanned by the lacing need never be so wide as to cause the above described undesirable and annoying skin chafing conditions.

20 I claim:

A corset having an insert for varying the size of the corset, comprising a narrow strip permanently secured to the corset, said strip having a row of hook eyelets on the free edge thereof; a **25** single relatively stiff but flexible strip having on one side thereof a row of hooks engaging said hook eyelets; and on the other side thereof a row of lacing eyelets; said corset having a vertical portion having a row of lacing eyelets; and a lacing passing through the eyelets of said second mentioned strip and said corset portion and flexibly connecting the same.

JOSEPHINE L. HOLT.
